UNITED STATES PATENT OFFICE.

LEWIS C. MYERS, OF BROOKLYN, NEW YORK, ASSIGNOR, BY MESNE ASSIGNMENTS, TO ROYAL TYPEWRITER COMPANY, INC., OF NEW YORK, N. Y., A CORPORATION OF NEW YORK.

CARRIAGE-FEEDING SPRING-BARREL FOR TYPE-WRITING MACHINES.

1,148,251.

Specification of Letters Patent. Patented July 27, 1915.

Original application filed June 12, 1909, Serial No. 501,693. Divided and this application filed March 31, 1911. Serial No. 618,123.

To all whom it may concern:

Be it known that I, LEWIS C. MYERS, a citizen of the United States of America, residing in the borough of Brooklyn, county 5 of Kings, and State of New York, have invented a certain new and useful Improvement in Carriage-Feeding Spring-Barrels for Type-Writing Machines, of which the following is a specification.

10 This invention relates to the carriage feeding spring barrel of a typewriting machine and the application is a division of my application Ser. No. 501,693 filed June 12, 1909.

15 The purpose of the invention herein described is to provide ball bearings and also a simple and effective construction by which the barrel and its carrying shaft may readily be assembled.

20 In the accompanying drawings: Figure 1 is a side elevation partly in section of so much of the apparatus as is thought necessary to illustrate the invention. Figs. 2 and 3 are respectively a front elevation and transverse section through a spring barrel 25 of modified construction as compared with what is shown in Fig. 1. Fig. 4 is a detail view partly in section showing a spring barrel shaft such as is employed in the construction of Figs. 2 and 3; and Fig. 5 is a 30 plan or front elevation of a spring barrel such as shown in Fig. 3 with the cover plate removed. Fig. 6 is an enlarged sectional view showing details of construction of the 35 form of spring barrel shaft used in the construction shown in Fig. 1. Fig. 7 is a view similar to Fig. 3 showing merely that the spring barrel shaft rod fitted in the spring barrel shaft sleeve may be square in cross section.

40 The spring barrel 7 is mounted (Fig. 1) to rotate upon a shaft composed of a plurality of parts indicated in detail in Fig. 6, —that is to say there is a shaft 8 carrying at one end a worm gear 10 and reduced in 45 diameter at the other end as at 8^a. Over the shaft fits a sleeve 9^a having an enlarged hub 9^b carrying on its periphery a hook 9^c for attachment to the hub of the inner end of the motor spring. The sleeve 9^a has a 50 part 9 of reduced diameter threaded at its end. The shoulder formed at the junction of the part 9 and enlargement 9^b is beveled as at 26. There is a tapered opening in the

side of the spring barrel in which fits a tapered ring 27 having in its inner face an 55 annular V-shaped groove forming part of a ball race containing balls 28. The other part of this race is formed by the bevel shoulder 26 and by an opposite coöperating bevel end of a collar 29 fitting over the reduced part 9 of the sleeve and secured thereto by a set screw 29^a. The reduced part 8^a of the shaft is flattened on one side and the end of the clamp screw 29^a, passing through the reduced part 9 of the sleeve, impinges 60 against the flat surface. This prevents rotation of the sleeve on the part 8^a of the shaft. On the threaded end marked 30 of the reduced part 9 of the sleeve is screwed a 65 collar or nut 31. This nut holds the parts 70 together before the spring drum is mounted on the shaft 8 and affords means for adjusting the bevels of the inner half of the race way. The tension of the motor spring may be adjusted by a worm 18 actuating 75 the worm gear 10 and having a bearing in a part 12 of the barrel supporting bracket. The reduced part 8^a of the shaft instead of being flattened on one side may be square 80 in cross section and the sleeve may have a corresponding bore. The ribbon mechanism may be driven by bevel gear 100 in the end of a stud shaft carrying at its other end a ratchet wheel 101 engaged by a spring 85 pressed driving pawl 102 pivoted in an arm on the side of the spring barrel.

Figs. 2 and 4 show a modification in which the spring barrel has a double ball bearing. The shaft is provided with a worm gear 32 engaged by a worm 33 to adjust the 90 tension of the spring. There is a sleeve having a hub 34 on which is the spring securing hook 9^c. Each of the shoulders formed by the hub is tapered as at 35 to form one-half of a ball race. One side plate 36 of the 95 spring barrel casing is formed with a cup shaped recess 37 in which is seated a hard metal cup shaped ring 38 forming one part of the ball race, the other part of which is formed by the bevel shoulder of the hub 34. 100 The opposite ball race is formed by the other tapered shoulder of the hub and the inner face of a ring plug 40 screwing into the hollow hub formed on the other side plate 41 of the spring barrel. The reduced 105 part 42 of the sleeve on this latter side of

the hub extends through the screw plug and receives a collar 43 having a clamping bolt 44 that passes through the collar and part 42 of the sleeve and impinges upon the shaft 44^a disposed within the sleeve and carrying at one end the worm gear 32.

Fig. 3 shows an elevation of the left hand side of Fig. 2. The side plate 41 of the spring barrel is shown as of skeleton construction, the body of which is of less diameter than the opposite side 36 and the connecting screws 45 pass through lugs 46 at the periphery of the plate 41.

Fig. 5 is an elevation showing the inner 15 face of side plate 36 of the spring barrel, it also being shown with symmetrically disposed openings 47.

Fig. 7 is a view similar to Fig. 3 and is intended merely to show that the reduced 20 part 8^a of the shaft may be square in cross section.

I claim:

1. Spring barrel mechanism for a type-writing machine, comprising a spring barrel provided with the outer part of a ball race way, a spring barrel shaft having a sleeve formed with a hub located within the barrel and having a tapered shoulder and means for attachment of the inner end of the spring, a screw for connecting the sleeve and shaft for positive rotation together, and a ball bearing, one part of the race way of which is formed by the tapered shoulder of the hub and the other part carried by the barrel.

2. Spring barrel mechanism for a type-

writing machine, comprising a spring barrel provided with the outer part of a ball race way, a spring barrel shaft having a sleeve formed with a hub located within the 40 barrel and having a tapered shoulder and means for attachment of the end of the spring, a screw for connecting the sleeve and shaft for positive rotation together, a ball bearing one part of the race way of 45 which is formed by the tapered shoulder of the hub and the other part carried by the barrel, a worm gear applied to one member of the shaft and a coöperating worm for effecting adjustment of the tension of the 50 spring.

3. Spring barrel mechanism for a type-writing machine, comprising a spring barrel provided with the outer parts of ball race ways, a two part shaft one of which 55 parts is a sleeve fitting over the other part and having a hub within the spring barrel, said hub having tapered ends and means for attachment of the inner end of the spring, means for connecting the two parts 60 of the shaft for positive rotation together, and a ball bearing at each side of the hub, part of the race-way of each ball bearing being formed by a tapered shoulder of the hub and the other parts carried by the 65 spring barrel.

In testimony whereof, I have hereunto subscribed my name.

LEWIS C. MYERS.
